ABSORBER FOR ANESTHETIC GAS
MACHINES

Le Roy G. Fox, Glendale, Calif., assignor to E & J
Manufacturing Company, Burbank, Calif., a
corporation of California

Application August 11, 1952, Serial No. 303,763

2 Claims. (Cl. 183—4.0)

1

My invention relates to an absorber for an anesthetic machine used in the administration of gas anesthesia to patients in hospitals.

An anesthetic machine is usually used which administers gas anesthesia through a closed mask system to the patient's lungs. The purpose of my invention is to place an absorber in the system between the anesthetic machine and the mask to absorb the CO₂ from the exhalations of the patient. As the system from the gas anesthetic machine to the patient's lungs is a closed circuit, the exhalations are contained in this line and it is often desirable to remove some or all of the CO₂ exhaled by the patient.

Prior to my invention a canister containing soda lime was placed in the gas circulation so as to absorb the CO₂. When the soda lime had become saturated with CO₂ it would be necessary either to stop the anesthesia to put in a new canister or to dilute the gas mixture with air while a new canister of soda lime was being placed in the line. By the use of my absorber a plurality of canisters is always available to be used either individually or in combination to remove the CO₂ from the anesthetic gas without at any time stopping the administration of the anesthesia to the patient or without any danger of air getting in and diluting the anesthetic gas.

By the use of my machine it also is possible to vary the amount of absorption of CO₂ so as to leave some of it in the anesthetic gas.

My present invention consists of an improvement on the invention described in my copending application Serial No. 149,802, filed March 15, 1950, now Patent No. 2,614,561, issued October 21, 1952.

Other objects and advantages of my invention will be apparent from the following description of the preferred embodiments thereof.

In the drawings:

Figure 1 is a plan view of my invention.

Figure 2 is a section taken on the line 2—2 of Figure 1.

Figure 3 is a section taken on the line 3—3 of Figure 2.

Figure 4 is a section taken on the line 4—4 of Figure 2.

Figure 5 is a partial section taken on the line 5—5 of Figure 1.

Figure 6 is a partial section taken through one of the canister seal plugs, showing it in the locked position.

Figure 7 is a partial section, similar to Figure 6 but showing the plug in a removable position.

Figure 8 is an inside view of one of the elements of the sealing plug.

2

Figure 9 is a top plan view of an element of the sealing plug.

Figure 10 is a bottom plan of the valve-actuating cam.

Figure 11 is a front view of the cam of Figure 10.

An absorber constructed in accordance with my invention has a head 1 and a base 2 forming the ends of a cylindrical shell 3. The flange 4 has a bore 5 therein to support my absorber on a column 6 of an anesthetic machine (not shown). My absorber is held in position on the column 6 by a set screw 7.

A plurality of cylindrical bores 8, 9 and 10 are formed in the head 1 directly opposite similar bores 11, 12 and 13 in the base 2. Between each corresponding bore in the head and base is positioned a canister-receiving tube 14. These tubes are force fitted in their respective bores and are airtight in the bores. Each of the bores 8, 9 and 10 is run completely through the head and is closed by a sealing plug, to be hereinafter described. Positioned in each of the tubes 14 is a removable canister 15 containing soda lime or other CO₂ absorbing material. These canisters 15 are removable through the head by merely pulling them out.

A sealing means 16 is inserted in the head to plug and make an airtight seal so that no air can enter the canister from the outside. These sealing means 16 comprise a body member 17 which has thereon an outwardly extending flange 18 to contact the outer surface of the head 1, a tapered surface 19 extending into a vertical surface 20. A control handle 21 is affixed to a shaft 22 passing through the body member 17 and having a flanged plate 23 forced thereon.

Between the sides of the tube 14 and the vertical surface 20 is placed a rubber O-ring 24 and above that is a coiled spring 25. The lower end of the shaft 22 is threaded as at 26 and carries thereon a collar 27. A coil spring 28 is placed between said collar and the flanged plate 23. A nut 29 is threaded upon the threads 26 to maintain the collar 27 and spring 28 upon the shaft 22 and to exert pressure against the flanged plate 23.

There is an upper extending cam 30 upon the flanged plate 23 and the shaft 22 carries thereon a cam rider 31. As will be seen from Figures 8 and 9, the cam 30 only extends over a small area of the flanged plate 23. A pin 32 is threaded into the body member 17 and fits in a hole 33 in the flanged plate 23 to prevent rotation of the body member 17 in relation to the flanged plate 23. When a sealing means 16 is inserted in any one

of the bores 8, 9 or 10, it is held in a nonrotatable position by means of a pin 34 threaded into the body member 17 and loosely fitting in a bore 35 in the head 1.

The sealing means 16 can only be inserted in the bores 8, 9 or 10 when the cam rider 31 is in engagement with the cam 30. After insertion in the bores 8, 9 or 10, the sealing means 16 is sealed therein by rotation of the handle 21 so that the cam rider 31 is disengaged from the cam 30, which then allows the spring 28 to force the flanged plate 23 upwardly and by means of the tapered surface 19, expanding the O-ring 24 into the sockets 36, forming an airtight seal at the head of the bore.

As shown in Figure 1, the handle 21 has pointers 37 to indicate whether or not the sealing means 16 is in a sealing position. When the pointer 37 is positioned at the "remove" position marked, the cam rider 31 is engaging the cam 30, forcing the flanged plate 23 downwardly, removing the tension on the O-ring 24 and allowing removal of the seal means 16 from the bore.

To indicate the length of time that a particular canister has been in use, any type of marking, such as the word "fresh" (39) and the minutes that the canister has been in use can be marked around the body member 17. The user of the anaesthetic machine can rotate the handle 21 in accordance with the length of time that the particular canister has been in use until he arrives at the word "remove," when he should change the canister.

In the head 1 is a pair of bores 45 and 46, which are connected to the inhalation side and the exhalation side of the anaesthetic breathing mask (not shown). The exhaling bore 46 has a nipple 47 forced therein which is connected to the rubber hose from the breathing anaesthetic mask, which carries away the exhalation of the patient. The bore 46 permits the exhaled gas from the mask to enter a cup-shaped chamber 48 which is closed by a flutter valve plate 49 so that any attempted suction through the bore 46 will cause the flutter valve plate 49 to seal the end of the cup-shaped chamber 48 while any pressure from the interior will cause the flutter valve plate 49 to rise and allow the pressure to escape into a chamber 50 in the head 1.

The chamber 50 is sealed by a plug 51 threaded thereinto, which carries a guide 52 for the valve stem 53 of the flutter valve plate 49.

The chamber 50 has a port 54 to permit exhaled gases to enter a valve chamber 55 in the head 1, closed by means of a screw plug 56. Radially extending from the central bore 55 are the passages 57, 58 and 59, connecting with the bores 8, 9 and 10, respectively, so that exhaled gases can pass therethrough and then down through the canisters of soda lime and out through the passages 60, 61 and 62, connecting the bores 11, 12 and 13 with a valve chamber 63 where the gas either passes downwardly into the gas bag 64 or out through the passage 65, past a flutter valve 66 in the head 1 into the chamber 67, through the exhalation bore 45 and into the breathing mask (not shown). The chamber 67 is sealed by means of a screw plug 68, identical to the screw plug 51, and has a guide for the valve stem of the flutter valve 66. A port 41 connects the chamber 67 with a source of fresh anaesthetic gas, indicated by the pipe 42. The flutter valve 66 prevents any reverse flow of gas or exhalation from the breathing mask through my absorber.

As it is not desirable to have all of the canisters at one time in the enclosed anaesthetic system and as it is often necessary to replace a canister 15 during the period of anaesthesia, I have provided means for selectively porting the exhaust gas through one or more of the canisters 15 at the same time so that one or more of the canisters 15 can be removed while at least one of the canisters 15 is still in the anaesthetic system. Hollow bosses 70 are threaded into the head 1. Threadedly connected to the bosses 70 are cylinders 71 which have holes 72 in their bottom ends through which are passed valve stems 73. Upon the valve stems 73 are collars 74 and plate valves 75. Between collars 74 and the bottom ends of the cylinders 71 are placed rubber O-rings 76. Springs 77 are positioned between the collars 74 and the plate valves 75, which force the plate valves 75 upwardly to close the valve ports 78 between the central bore 55 and the passages 57, 58 and 59, respectively.

A valve cam 79 is carried by a control shaft 80 journaled in the plug 56. An indicator knob 81 is mounted on the control shaft 80. The valve cam 79 can selectively contact and depress one or more of the valve stems 73, opening one or more of the valves 75 to port the gases from the valve chamber 55 to one or more of the canisters 15 while leaving at least one of the canisters closed off by its valve 75.

To prevent opening of the closed anaesthetic circuit to the atmosphere during the removal of any of the canisters while the machine is in operation, I provide the three valves 88 adapted to close off the bores 11, 12 and 13 from the valve chamber 63. These valves 88 are carried on valve stems 82 slidable in the cylinders 83 threaded to the bosses 84, which are threaded at 85 to the base 2. The springs 87 are positioned between the collars 86 and the bosses 85 to maintain the valves 88 in closed or sealing engagement. The valve stems 82 are positioned directly under the corresponding valve stems 73 so that when the cam 79 opens one of the valves 75, it similarly opens the valve 88 directly thereunder, thus permitting the passage of the gas through the corresponding canister 15 and out into the valve chamber 63, but any of the valves 75 which are closed will have their corresponding valve 88 closed, thus preventing any leakage into the enclosed gas cycle, and permitting the removal of the sealed-off canister 15.

I claim:

1. In an absorber, a head and a base forming supports for a plurality of tubes, said head having an intake port and an outlet port, selective valves in said head to connect said intake port with one or more of said tubes, said base having an outlet from said tubes, selector valves in said base to connect said tubes to said outlet port, means for actuating said selector valves, removable plug means carried by said head to permit opening said tubes, comprising: a body member, a control shaft, a flanged plate carried by said shaft, an O-ring positioned on said body above said flanged plate, a cam surface on said flanged plate, a cam rider on said shaft adapted to engage said cam surface and space said flanged plate from said body, and means for yieldably forcing said flanged plate against said body when said cam surface and cam rider are disengaged.
2. In an absorber, a head and a base forming supports for a plurality of tubes, said head having an intake port and an outlet port, selective valves in said head to connect said intake port

with one or more of said tubes, said base having an outlet from said tubes, selector valves in said base to connect said tubes to said outlet port, means for actuating said selector valves, flutter valves between said intake port and said first mentioned selector valves and between said outlet port and said second mentioned selector valves, removable plug means carried by said head to permit opening said tubes, comprising: a body member, a control shaft, a flanged plate carried by said shaft, an O-ring positioned on said body above said flanged plate, a cam surface on said flanged plate, a cam rider on said shaft adapted to engage said cam surface and space said flanged plate from said body, and means for yieldably forcing said flanged plate against said body when said cam surface and cam rider are disengaged.
